ATTORNEY

UNITED STATES PATENT OFFICE.

NORRIS ELMORE CLARK, OF PLAINVILLE, CONNECTICUT.

METAL FABRIC.

1,101,176.

Specification of Letters Patent. Patented July 21, 1914.

Continuation of application Serial No. 480,976, filed March 2, 1909. This application filed April 1, 1912.
Serial No. 687,597.

To all whom it may concern:

Be it known that I, NORRIS ELMORE CLARK, a citizen of the United States, and resident of Plainville, in the county of Hartford and State of Connecticut, have invented certain new and useful Improvements in Metal Fabrics, of which the following is a specification.

My invention relates particularly to what are commonly termed expanded metal fabrics and this application is a continuation from application #480,976 filed March 2nd, 1909 as to all matter illustrated in Figures 1, 2, 3, 4 and 6.

The special object is to provide more rigidity and holding power for such structures as concrete floors and roofs and plaster side walls and partitions. It comprises the combination of parallel ribs or beam-like members and lathing integral therewith, in this particular form claimed in this application the beam-like members are formed by grooving or longitudinally corrugating strips of metal into the form of ribs projecting from the general plane of the expanded portion. The edges of each beam are bent back reversely so as to form relatively shallow channels facing in the opposite direction to the central groove in the beam. This gives greater lateral stiffness and also facilitates the manufacturing without straining or rupturing the metal. The sides of the beams or ribs may be perforated or otherwise recessed to permit the plaster, cement or mortar from one side to pass through and to interlock with that on the other. The portions punched out or some of them may be left integral at one edge of the perforations and bent over so as to form projecting fingers for attachment purposes if desired. In the form shown the expanded lath sections consist of zig-zag bent strands connected to each other and arranged on edge with diamond-shaped meshes between, the general direction of the strands of the sections being inclined relative to the beams. Preferably in the form shown the expanded portions lying between two beams consist of two sections united by a strip or rib midway between the beams, the inclination of the strands of the adjacent sections being in opposite directions.

Fig. 1, is an elevation of a fragment of a fabric embodying the improvements of my invention. Fig. 2, is an edge view of the

same. Fig. 3, is a horizontal sectional view of the structure. Fig. 4, is a fragmentary section of a beam or rib showing attaching fingers stuck from the sides of the beam and bent outwardly. Fig. 5, is a fragmentary section of a modified form of the intermediate rib or strip. Fig. 6, is a fragmentary section showing a beam with recesses formed by indenting.

In the preferred form of Figs. 1, 2 and 3 the beams or ribs 1 and 2 are connected by expanded mesh portions consisting of the sections 3 and 4 united midway by the strip or rib 5. Each beam member is formed by bending, corrugating or grooving a strip of metal longitudinally so as to form a groove or channel 6. The edges such as 7, 7 are reversely bent so as to afford relatively shallow channels such as 8, 8 facing in the opposite direction to the channel 6. The sides of the beams may be perforated or recessed as at 9 so as to permit the inflow of cement or plaster and thus prevent formation of lines of cleavage which exist where the sides of the ribs are perfectly plain and imperforate. Where the sides are perforated the cement can pass through so that the cement is continuous through the beams and the full strength of the metal is thus developed.

In the form shown in Fig. 4 tangs, clips or fingers such as 10, 10 are cut from the sides of the beam and bent outwardly to afford means for attaching the fabric to a support or attaching other devices to the fabric.

In the form shown in Fig. 6 the sides of the beam are indented as at 11 so as to afford an anchorage for the cement to prevent lines of cleavage but without cutting through the metal.

In the form shown each expanded section consists of narrow strands such as 12 and 13 united to each other at a plurality of points such as 14 and 15 and arranged on edge relative to the plane of the fabric and extending generally in a direction inclined, or diagonal relative to the direction of the beams.

The general direction of inclination of the strands in section 3 is opposite to the general direction of inclination of the strands in section 4, the two sections being united along the central strip or rib 5 midway between the beams 1 and 2, the strands in sec-

tion 3 being inclined upward and to the left from the central rib and the strands in section 4 being inclined upward and to the right.

5. The central rib in the form shown in Figs. 1 and 3 is slightly corrugated transversely so that the expanded section from beam to beam is of substantially uniform thickness.

In the form shown in Fig. 5 the central 10 rib 51 is grooved longitudinally so that the channel 52 faces in the same direction as the channel 6 in the main ribs or beams.

The strands it will be noted stand in a general edgewise direction relative to the plane 15 of the fabric, the strands in section 3 being tilted particularly at their bonds or points of connection 14 and 15 upward toward the right as viewed in Fig. 3 while the bonds in section 3 are tilted upward toward the left.

20 This insures a better distribution of the cement, plaster or mortar. The small sized diamond meshwork also tends to distribute the strain more equally in all directions.

The sides of the ribs or beams extend substantially transverse to the plane of the fabric and with their reversely grooved or flanged edges or lips inclined at substantially the same angles as the edgewise inclination of the adjacent connecting strands.

25 In the preferred form shown, there are two sections of expanded meshwork united midway between each two adjacent ribs or beams and the strands of the two sections are inclined edgewise in reverse directions, the direction 30 of inclination of the strands of each section corresponding to the direction of inclination of that edge of the adjacent beam with which they are united. This structure has the strands bent directly from the flanged 35 edges without twisting and thus avoids strain in manufacture. It also means that the maximum strength of the metal is available to resist strain when in use. It will be obvious that the fabric may be of any 40 width or length and have as many beams and reticulated sections as desired.

45 What I claim is:—

1. As a new article of manufacture, a slotted and expanded sheet metal structure, 50 consisting of slotted and unslotted portions, and having relatively deep ribs consisting of bent unslotted portions of the metal, an unslotted strip intermediate of the deep ribs, at least some of the deep ribs having 55 their edges adjacent to the slotted portions reversely bent and facing the opposite side of the structure from the deep ribs themselves and oppositely directed slats connecting said strip and the edges of said deep ribs 60 substantially as described.

2. As a new article of manufacture, a slotted and expanded sheet metal structure, 65 consisting of slotted and unslotted portions, and having relatively deep spaced ribs consisting of bent unslotted portions of the

metal, a central strip between each pair of deep ribs the inner edges of the deep ribs being reversely bent so as to face in the opposite direction from the deep ribs themselves and two series of slats connecting said strip with the reversely bent edges of said deep ribs, substantially as described.

3. As a new article of manufacture, a slotted and expanded sheet metal structure 70 consisting of slotted and unslotted portions and having deep ribs consisting of bent unslotted portions of the metal, said ribs having relatively narrow reversely bent lips at their edges, a central unslotted strip and a series of oppositely directed slats connecting said strip with said reversely bent lips, the outer portions of the deep ribs having 75 perforations therein substantially as described.

4. An expanded metal fabric consisting of 80 longitudinally corrugated ribs having reversely bent edges forming channels facing in opposite directions and an expanded metal section connecting the reversely bent edges and consisting of two parts united 85 midway between the corrugated ribs, the strands of the two parts being inclined in opposite directions.

5. An expanded metal fabric consisting of 90 longitudinally corrugated ribs having reversely bent edges forming channels facing in opposite directions and an expanded metal section connecting the reversely bent edges and consisting of two parts united 95 midway between the corrugated ribs, the sides of the ribs having openings so constructed so as to prevent the formation of 100 lines of cleavage.

6. A reticulated metal fabric consisting of 105 longitudinally corrugated ribs having reversely bent edges forming channels facing in the opposite direction, the sides of the ribs being perforated to permit cement or plaster to be interlocked through the same and a reticulated section connecting the reversely bent edges of the ribs and consisting 110 of strands with relatively small openings there between.

7. An expanded metal fabric consisting of 115 longitudinally corrugated ribs having reversely bent edges forming channels facing in opposite directions and an expanded metal section connecting the reversely bent edges and consisting of two parts united 120 midway between the corrugated ribs, said expanded metal section consisting of bent strands inclined edgewise to the general plane of the fabric and connected together to form substantially diamond-shaped meshwork, the strands of the said two parts of 125 the section being inclined in opposite directions.

8. A reticulated metal fabric, comprising 130 beam members each having a relatively deep main channel portion with reversely bent

marginal flanges forming side channels facing in the direction opposite to the main channel and a reticulated section connecting the adjacent marginal flanges of the beams, and means in the sides of the beam members for preventing the formation of lines of cleavage.

9. A metal fabric comprising a plurality of deep folded non-expanded ribs, each having a main channel open at one face of the fabric and reversely bent edges forming channels open toward the opposite face of the fabric and expanded metal sections integrally connecting the adjacent edges of adjacent ribs, each expanded section con-

sisting of a plurality of relatively narrow bent strands connected together to form substantially diamond-shaped openings; the said strands being arranged inclined edge-wise to the general plane of the fabric, each of the reversely bent edges of the ribs being inclined to the general plane of the fabric at substantially the same angle as the edge-wise inclination of the strands connected thereto.
